Primary Examiner — Eric Goodman*Assistant Examiner* — Bao-Yen Nguyen(74) *Attorney, Agent, or Firm* — Design IP(57) **CLAIM**

The ornamental design for a graphical user interface for a portion of a display screen, as shown and described.

DESCRIPTION

FIG. 1 is a front view of an image of a graphical user interface for a portion of a display screen showing my new design. The broken line showing of a portion of a display screen in FIG. 1 forms no part of the claimed design. The broken line showing of text and portions of the graphical user interface in FIG. 1 represents environmental subject matter and forms no part of the claimed design.
